UNITED STATES PATENT OFFICE

NEILSON K. SMITH, OF LOS ANGELES, CALIFORNIA, ASSIGNOR TO BYRON-JACKSON CO.,
OF LOS ANGELES, CALIFORNIA, A CORPORATION OF DELAWARE

ELEVATOR LATCH

Original application filed April 7, 1930, Serial No. 442,259. Divided and this application filed June 29, 1931. Serial No. 547,523.

This invention relates to side door elevators of the type used in the raising and lowering of well casing, tubing, and the like, in the operations of drilling a well and maintaining the same in production.

An object of the invention is to provide a latch that operates in a vertical plane, the path of movement of said latch also being in a vertical plane.

10 This is a division of my copending application, Serial No. 442,259, filed April 7, 1930, now matured into Patent No. 1,824,412.

Other objects and advantages of the invention will be apparent from a detailed description of the invention when taken in conjunction with the accompanying drawings, in which

Figure 1 is a plan view of a side door elevator constructed in accordance with the provisions of this invention;

Figure 2 is a front elevation of Fig. 1;

Figure 3 is an elevation from the right of Fig. 4;

25 Figure 4 is a fragmental view, partly in section, on the line indicated by IV-IV, Fig. 2;

Figure 5 is a fragmental front elevation of a modified form of the invention showing the latch and a portion of the door; and

Figure 6 is a fragmental plan view of the modified form of the invention, partly in section, on the line indicated by VI-VI, Fig. 5.

Referring at present more particularly to Figures 1 to 4 of the drawings, two members or jaws 8, 9 are provided. The jaw 8 may be considered the body of the tool and the jaw 9 is commonly known as the door. The body 8 and door 9 are hingedly connected by a pivot or pin 10, the mounting of which is preferably of special construction to secure rising of the door relative to the body when the door is being opened and lowering of said door when the door is to be closed. This special mounting of the pivot will now be described:

The pivot pin 10 is not positioned parallel to the axis of the elevator bore 11 but is at an angle to said axis. Viewed from either side of the body 8, the pivot 10 extends aslant downwardly and outwardly, as shown in Fig. 50 3. Viewed from a position in front of the door of the elevator, the pivot 10 is positioned so that it extends aslant inwardly and downwardly, as shown in Fig. 2. The end portions of the pivot 10 are mounted in upper and lower ears 12, 13 of the body 8, said pivot being preferably fixed in said ears. The pivot 10 passes through upper and lower ears 14, 15 of the door 9, said ears 14, 15 being, in this instance, disposed between the 55 ears 12, 13. The holes 16 in the ears 12, 13, 14, 15 are constructed so that their axes extend aslant to the axis of the bore 11, the slant being the same as described above for the pivot in order to secure the desired slant 60 of the pivot. When the door is open it is supported by reason of the ear 15 resting on the ear 13 and when said door is closed it is not only supported by the ear 13 but is 65 also supported at its free end by a shoulder 70 17 on the body 8. The lower face 18 of the ear 15 and the upper face 19 of the ear 13, being adapted to engage, are disposed at a right angle to the pivot 10 so that in the 75 opening movement of the door 9 perfect hinging takes place and the full area of the faces 18, 19 are in engagement. Preferably the lower face 20 of the ear 12 and the upper face 21 of the ear 14, also, are disposed at 80 a right angle to the pin, though said faces 20, 21 need not necessarily be in engagement but, preferably, are slightly spaced as indicated in Fig. 2.

The slant of the pivot 10, as viewed from either side of the elevator and as viewed from the front, has been described above, and in this instance the amount of slant is such that the upper and lower ends of the axis of the pivot are substantially on the same 90 arc of a circle of which the axis of the bore

11 is the center, or, in other words, the upper and lower ends of the pivot are approximately the same distance from the axis of the bore.

- 5 The body 8 is provided at its opposite ends with supporting trunnions 22, which are in alignment and the prolonged axes of which pass through the axis of the bore 11. These trunnions 22 need not be further described, 10 nor the latches 23, which cooperate therewith, as they constitute no portion of the present invention and may be of any suitable construction for connecting the elevator with links of a bail of the character employed with 15 elevators of this type.

The bore 11 comprises the concave inner face 24 of the body 8 and the concave inner face 25 of the door 9. The face 24 extends over 180° of circular measurement while the 20 face 25 extends over considerably less than 180° of circular measurement. The face 24 is substantially circular for 180° and said face has forwardly and outwardly flaring portions 26 so as to readily admit of the 25 entrance of the casing or other member that is to be supported by the elevator.

Though any suitable latch may be employed with the construction hereinbefore described, there is provided a special latch 30 which will now be described: Mounted in the body 8 and projecting forwardly therefrom is a latch pivot 30, said pivot being horizontally positioned or in other words, lying in a plane at right angles to the axis 35 of the bore of the elevator. It is also positioned at a right angle to a vertical plane passing through the trunnions 22. Hung on the pivot 30 is a latch 31, the tip 32 of which is adapted to engage with a shoulder 33 that is formed by the front face of a lug 34 that projects laterally from one end portion 40 of the door 9. Preferably the shoulder 33 extends aslant inwardly toward the bore and the front face of the latch tip 32 has a 45 complementary slant, as shown at 35, so as to closely cooperate with the shoulder 33 to hold the door in closed position. This construction of the shoulder 33 and face 35 tends to prevent opening of the latch, since, to 50 open said latch, it is first necessary to move the door 9 inwardly in order that said latch may pass the outer end of the shoulder 33.

The latch includes an upwardly extending 55 arm 36 and said latch is yieldingly held in latching position by a coil spring 37 which has one end resting against the latch 31 outwardly from the pivot 30 while the other end of said spring rests within an angular lug 38 that projects forwardly from the body 60 8. Between the lug 38 and the body is a slot 39 into which the latch projects.

The arm 36 is provided with a handle 40 that projects laterally from said arm. The handle 40 projects into a plane that passes 65 through a handle 41 projecting outwardly

from the middle portion of the door, thus facilitating release of the latch with one hand of the operator and opening of the door with the operator's other hand.

The foregoing described construction operates as follows:

Assuming that the elevator bails are connected with the trunnions 22 and that the door 9 is open, the elevator will be swung into a position to receive the casing or tubing in the recess 24 of the body 8 and the operator will then close the door 9 and coincidentally the elevator will be raised to cause the coupling or collar to seat on the seats 27, 28.

These elevators are operated very rapidly and it requires considerable quickness on the part of the operator to close the door as the closing must be done while the elevator is rising into position to engage beneath the coupling or collar. This elevator lends itself readily to rapid operation, as the operator has only to slam the door, and if it is slammed hard enough to permit the lug 34 to pass the shoulder 32 of the latch, any subsequent opening pressure exerted by the casing on the gate serves merely to lock the latch more firmly, instead of tending to release it. This desirable locking tendency is created by slanting the cooperating latch and lug faces so that the door must close tightly to release the latch, and open slightly as the latch is fully locked.

When it is desired to release the elevator from the tubing or casing, the elevator will be lowered to disengage the seats 27, 28 from the coupling or collar, the latch will be retracted and then the door will be opened. Any outward pressure on the door 25 tends to lock the latch, thus guarding against accidental opening when casing is being supported by the elevator, but when the casing is loosely contained within the elevator, the door can readily be forced inward far enough to retract the latch.

Now referring more particularly to Figures 5 and 6 of the drawings, which illustrate a modified form of the latch, the elements that correspond in function to those hereinbefore described, are indicated by the same reference characters with the addition of the suffix "a."

The principal difference between this latch construction and that above described is that this modified latch is mounted on the door and because of this certain modifications of the construction are necessary or advisable. The coil spring 37a has one end in engagement with an upwardly extending arm 42 of the latch 31a and has its other end engaging within a seat 38a in the door. In this instance, the lug 34a is angular and projects forwardly from the body 8a and the latch 31a engages behind the tip of the lug 34a. The latch 31a is mounted in a vertical slot 39a in the door and the pivot 30a extends across

said slot and has its opposite ends extending through holes 43, 44 in the door. The arm 36a is of angular construction and terminates in a laterally extending handle 40a.

5 It will be clear that the two forms of latch operate substantially alike and that they both operate in a vertical plane, by rotation about a horizontal axis.

I claim:

10 1. An elevator comprising a body provided with members pivoted together and recessed to form the bore of the elevator, one of said members provided with a horizontal pivot projecting forwardly therefrom and offset from the bore of the elevator, the other member provided with a lug, and a latch mounted on said pivot engageable with the lug.

20 2. An elevator comprising a body provided with members pivoted together and recessed to form the bore of the elevator, one of said members provided with a horizontal pivot projecting forwardly therefrom and offset from the bore of the elevator, the other member provided with a lug, a latch mounted on said pivot engageable with the lug, the face of the lug engageable by the latch extending aslant inwardly toward the bore of the elevator.

30 3. An elevator comprising a body provided with members pivoted together and recessed to form the bore of the elevator, one of said members provided with a horizontal pivot projecting forwardly therefrom and offset from the bore of the elevator, the other member provided with a lug, and a latch mounted on said pivot engageable with the lug, that portion of the face of the latch that engages the lug extending aslant inwardly toward the bore of the elevator.

40 4. An elevator comprising a body and a door pivoted together and recessed to form the bore of the elevator, a horizontal pivot projecting forwardly from the body, the axis of said pivot being in a plane that is offset from the bore of the elevator, a lug projecting laterally from one end portion of the door and provided with a shoulder, and a latch hung on said pivot and adapted to engage behind said shoulder.

50 5. An elevator comprising a body and a door pivoted together and recessed to form the bore of the elevator, a horizontal pivot projecting forwardly from the body, the axis of said pivot being in a plane that is offset from the bore of the elevator, a lug projecting laterally from one end portion of the door and provided with a shoulder, and a latch hung on said pivot and adapted to engage behind said shoulder, the rear face of said shoulder extending aslant inwardly toward the door.

60 6. An elevator comprising a body and a door pivoted together and recessed to form the bore of the elevator, a horizontal pivot

projecting forwardly from the body, the axis of said pivot being in a plane that is offset from the bore of the elevator, a lug projecting laterally from one end portion of the door and provided with a shoulder, and a latch hung on said pivot and adapted to engage behind said shoulder, the front face of the latch-tip extending aslant toward the door.

7. An elevator comprising a body and a door pivoted together and recessed to form the bore of the elevator, a horizontal pivot projecting forwardly from the door, the axis of said pivot being offset from the bore of the elevator, an angular lug projecting forwardly from the body, and a latch hung on said pivot and adapted to engage behind the tip of said latch.

8. An elevator comprising a body and a door pivoted together and recessed to form the bore of the elevator, a horizontal pivot projecting forwardly from the door, the axis of said pivot being offset from the bore of the elevator, an angular lug projecting forwardly from the body, and a latch hung on said pivot and adapted to engage behind the tip of said lug, that face of the lug engaged by the latch extending aslant inwardly toward the door.

9. An elevator comprising a body and a door pivoted together and recessed to form the bore of the elevator, a horizontal pivot projecting forwardly from the door, the axis of said pivot being offset from the bore of the elevator, an angular lug projecting forwardly from the body, and a latch hung on said pivot and adapted to engage behind the tip of said lug, the face of the latch tip that engages the lug extending aslant inwardly toward the door.

10. An elevator comprising a pair of members hinged together and recessed to form the bore of the elevator, one of said members provided with a horizontal pivot on the end opposite said hinge, the other member provided with a lug on the end opposite said hinge, a latch mounted on said pivot engageable with the lug, the face of the lug engageable by the latch being slanted to form an acute angle with a plane normal to said pivot, the direction of said slant being that which will impede opening rotation of said latch when opening force is applied to said members.

11. An elevator comprising a body provided with members pivoted together and recessed to form the bore of the elevator, one of said members being provided with a lug at its free end and the other member being provided with a horizontal pivot adjacent its free end, the axis of said pivot lying substantially parallel to the direction of initial movement of said lug when said body members are moved from their closed to their open position, and a

latch mounted on said pivot having a face engageable with a face of said lug and being rotatable about said pivot into either latched or unlatched position.

5 12. An elevator as described in claim 11 further characterized in that the engaging faces of said latch and lug lie at a slight angle to the plane of rotation of said latch about said pivot, the direction of said angle 10 being such that opening movement between said lug and latch positively locks said latch against rotation into unlatched position.

Signed at Los Angeles, California, this 19th day of June, 1931.
